UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SIDE-SLIPPING WEFT DETECTOR FOR LOOMS.

Application filed June 9, 1926. Serial No. 114,799.

This invention relates to improvements in side slipping weft detectors for looms and it is the principal object of the invention to provide a detector of this type which shall 5 exert very little pressure on the yarn but at the same time be reliable in operation.

Certain types of yarn such as rayon are so fine that a bobbin of the ordinary size will last sufficiently long so that if the usual 10 feeler were employed the yarn would be injured by abrasion due to the pressure of the detector against a portion of the bobbin. It is a further object of my invention to provide a detector more particularly adapted that 15 use with fine yarns and so constructed that the normally moving part is extremely light and held in position by a delicate spring which can be deformed with a very light resultant strain on the yarn.

When weft detectors are applied to the usual form of automatic box loom it is customary to put the detector on the magazine side of the loom, an arrangement which permits the connections between the controller of the detecting mechanism and the magazine to be very short and it is a further 25 object of my invention to utilize an angularly movable support for the detector to control the actuator usually employed on multi-color weft replenishing looms.

It is usually found that when the advancing supply of weft engages the detector the latter tends to rebound and it is necessary to employ a spring sufficiently strong to prevent 35 this tendency, otherwise the detector wire rebounding away from the yarn may give a false indicating movement and it is a further object of my invention to provide a very light detector with a correspondingly small 40 tendency to rebound so that a light spring may be used.

With these and other objects in view which will appear as the description proceeds, my invention resides in the combination and 45 arrangement of parts hereinafter described and set forth in the claims.

In the accompanying drawings wherein I have shown a convenient embodiment of my invention,

Fig. 1 is a top plan view of my detector showing the same in full lines in normal

position and in indicating position in dotted lines, parts being in section,

Figs. 2, 3, and 4 are vertical sections on lines 2—2, 3—3, and 4—4, respectively, of Fig. 1,

Fig. 5 is a detail view of the detector showing the same compressed by a bobbin having sufficient yarn for continued weaving, and

Fig. 6 is an enlarged vertical section on line 6—6 of Fig. 5 showing the method of mounting the slideable detector on the angularly movable support.

Referring to the drawings it will be seen that I have provided a breast beam 10 and a loomside 11 to which is bolted the foot 12 of a weft replenishing mechanism which may be of the type set forth in Patent No. 1,030,748. Said foot supports a stud 13 on which is pivoted a transerrer arm 14 having 65 depending fingers 15 supporting any appropriate form of transerrer latch (not shown).

Secured to the loomside 11 is a bracket 16 in which is mounted for vertical reciprocation a block 17 having pivotally mounted 75 thereon an actuator lever 18. The inner end of said lever is connected to a rod 19 and the outer end thereof is movable vertically in a slot 20 formed in an upstanding horn 21 cast preferably as an integral part of the 80 stand 16. On each detecting beat of the loom the block 17 descends and if there is no obstruction offered to the outer end of the actuator the latter will move downwardly about the connection thereof with rod 19 as 85 a pivot, a condition existing so long as there is sufficient yarn present. When insufficient yarn is present, however, an obstruction to be described will be moved into the path of the actuator, this obstruction forming a 90 pivot about which the actuator moves downwardly to depress rod 19 and indicate to the replenishing mechanism, all as set forth in the aforesaid patent. The matter thus far described, with the exception of the obstruction or controller is of common construction and forms no part of my present invention.

In carrying out my improvements I extend the stand 16 to the right as at 30 in Fig. 1 and secure thereto as by screws 31 a 100 guide 32 having spaced walls 33 and 34. The forward end of the guide has a partition

35 extending between the walls to receive the forward thrust of a compression spring 36 the rear end of which presses against a depending wall 37 formed on a slide 38. Said slide 5 is guided for front and back movement between the walls and is restrained against upward movement by a cap 39 held as indicated in Fig. 1 to the guide 32 by screws 40. The slide is provided with a recess 41 10 slightly larger than the spring 36 to guide the latter as the same is compressed and expands.

An adjusting screw 42 is mounted in the slide 38 and engages the cap 39 to limit rearward movement of the slide 38 under influence of the spring 36. Said screw is received by a finger 43 extending to the left as indicated in Fig. 1 and in front of the stud 44 carried by the transferrer fingers 15. 20 At the time of transfer the stud is moved forwardly to engage the finger 43 and move the slide 38 to the front as is common in detectors employed on the magazine end of weft replenishing looms.

25 The slide 38 is provided with an arm 45 extending to the left from the rear end thereof and said arm is provided with a vertical stud 46 and a pin 47 to the rear of the stud. A detector carrier 48, preferably of 30 rectangular cross section as indicated in Fig. 4, is welded or otherwise secured to the bearing 49 which moves pivotally about stud 46. The rear end of said carrier is provided with a bearing portion 50 normally substantially 35 parallel to the axis of the shuttle and said carrier is further provided with a bent portion 51. Said bent portion is provided with a pair of bearings 52 and 53, the latter bearing being open as indicated in Fig. 40 6 and being in alignment with a forward bearing 54 in the bearing portion 50.

The other end of the carrier is extended to the left of the stud 46 and bent as at 45 to move on a flat area 56 of horn 21 when called upon to do so. The bent end 50 is normally held out of the path of the actuator lever 18 by a torsion spring 57 one end of which bears against arm 45 as at 58 and the other end of which engages the carrier as at 59, moving the latter against pin 47.

55 The detector proper is formed of a wire 60 having two spaced substantially parallel forwardly extending arms the shorter of which, indicated at 61, passes through the bearing 51 and the longer of which, indicated at 62, passes through aligning bearings 53 and 54. Said longer arm 62 is provided with a collar 63 which may be formed by upsetting the wire or by welding a washer thereto or in any other manner and there is provided a light compression spring 64 located between the bearing portions 50 of the carrier and the collar 63. The rear face 65 of the detector 60 is provided with teeth 65 proportioned to enter the yarn on the bobbin

under action of spring 64. Said spring 64 is preferably stronger than the torsion spring 57.

Under normal conditions the detector and carrier will be in the full line position indicated in Fig. 1 and as a bobbin provided with sufficient weft advances the teeth 65 will be embedded in the yarn and the detector 60 will slide forwardly with respect to the carrier 48 to a position similar to that indicated in Fig. 5, the bent controller end 55 being held out of the path of the actuator 18 so that the latter may descend without interruption. When insufficient weft for weaving is present, however, a substantially bare bobbin will engage the detector teeth and inasmuch as the latter are offset from the stud 46 continued forward movement of the bobbin B in shuttle S will move the carrier and detector as a unit about stud 46 to 18 some such a position as that indicated in dotted lines in Fig. 1. The result of this angular movement is to move the controller end 55 of the carrier under the actuator lever 18 to interrupt the downward movement of the latter and communicate indication of 90 weft exhaustion to the magazine.

From the foregoing it will be seen that I have provided a very light weft detector of the side slipping type wherein a light carrier is movable about its axis and has mounted thereon for sliding movement a detector element held in normal position by a light spring. It will furthermore be seen that the carrier is made as a part of the controller 100 for the actuator which effects a change in the operation of the loom, such as weft replenishment.

Having thus described my invention it will be apparent that changes and modifications 105 may be made therein by those skilled in the art without departing from the spirit and scope of the invention, and I do not wish to be limited to the details herein disclosed but what I claim is:

1. In a side slipping weft detector for looms, an actuator to effect a change in the operation of the loom, a pivoted carrier adjacent the actuator and having a controller end rigid therewith for said actuator, a detector slidably mounted on the carrier, said controller end of the carrier being normally out of the path of the actuator and movable into the path of said actuator when the carrier has a pivotal movement, said detector sliding on the carrier when sufficient weft is present and preventing pivotal movement of the carrier by contact of the detector with the weft, and said detector sliding along a bobbin having insufficient weft to impart pivotal movement to the carrier to move the controller of said carrier under the actuator.

2. In a side slipping weft detector having a detecting surface to engage and be moved laterally and forwardly by motion derived

from the surface to be detected, an actuator lever having a regular movement on each detecting beat of the loom, a weft detector, a carrier on which the detector is slidably mounted, and a pivotal support for the carrier, a portion of the carrier lying on that side of the pivotal support opposite the de-

tector but rigid with the part in which said detector slides being movable into the path of the actuator when the detector has a movement to indicate weft exhaustion. 10

In testimony whereof I have hereunto affixed my signature.

OSCAR V. PAYNE.
